UNITED STATES PATENT OFFICE.

WILLIAM W. BOLLS, OF WASHINGTON, DISTRICT OF COLUMBIA.

BEAD THREADING OR DISPLAY BOX.

Application filed March 14, 1922. Serial No. 543,632.

To all whom it may concern:

Be it known that I, WILLIAM W. BOLLS, a citizen of the United States, residing at Washington, District of Columbia, have invented certain new and useful Improvements in Bead Threading or Display Boxes, of which the following is a specification.

This invention relates to certain new and useful improvements in display boxes, and

10 pertains more especially to boxes which are capable of multitudinous uses as for instance the display of merchandise of various characters; ladies' work boxes, bead threaders and toilette boxes, as will be more fully

15 hereinafter set forth in greater detail.

The primary object of the invention is to provide a box structure wherein the box proper is equipped with a cover serving to protect the contents against dirt, dust and varying climatic conditions; which cover upon removal serves as a means for rotatably supporting the box so that the contents of the latter can be selectively brought to lie directly in front of the user

20 so as to be more readily accessible for purpose of inspection or removal.

A further object of the invention is to provide a structure wherein latching means is provided to hold the box against rotation following movement thereof, and to easily release the box and allow of free rotation, without the separate operation or manipulation of the latching means.

Still further, the invention aims to provide a box cover having a finger engaging knob to allow of easy removal of the cover, which knob also forms a journal for rotatably supporting the box.

Still further the invention aims to provide means for supporting the box in true horizontal position from the cover and for permitting the box to freely turn with relation to the cover.

In the drawings:—

45 Figure 1, is a central longitudinal sectional view of the invention with the parts arranged in display position;

Figure 2, is a top plan view of the cover;

50 Figure 3, is a top plan view of a box having partitions therein;

Figure 4, is a top plan view of the invention as applied to a bead threader;

Figure 5, is a section on line 5—5 of Figure 4;

Figure 6, is a side elevation of Figure 4, 55 and

Figure 7, is a reduced top plan view of the cover.

In proceeding in accordance with the present invention a box 1 is provided having 60 a cover 2 which parts may be made of tin or other suitable material such as glass, pottery, celluloid, silver, nickel, or wood. The box is formed with a central struck-out concavo-convex part 3 forming a downwardly 65 facing socket, while the cover is formed with a similar struck-out part 4 forming an upwardly projecting combined hand knob and journal. For the purpose of facilitating gripping of the knob by the fingers same may be formed with opposed finger-receiving 70 depressions 5 as depicted in the drawings.

Normally the cover seats on the box so as to protect the contents of the latter, and 75 when it is desired to expose the contents the cover is removed and the box superimposed thereon with the knob 4 projecting into the socket 3 as illustrated in Figure 1 of the drawings. For the purpose of holding the box in a true horizontal plane and for allowing same to be more freely rotated, the cover may be provided with a circular series of small spaced struck-out 80 teats 6 having rounded domes that engage the under face of the box bottom and function as anti-friction bearings.

The invention also provides means to 85 latch the box against free rotation by holding same in any selected position to which 90 the box may be rotated and accordingly the bottom of the box is provided with a latch formed by a circular or ring like depression or groove 7, with the central portion within the groove bowed upwardly to form a downwardly facing keeper 8 which receives one 95 of the teats 6 and by frictional engagement therewith holds the box against rotation. The weight of the box contents will obviously exert sufficient pressure to cause the 100

keeper to frictionally engage against the teat so as to effectively latch the box, while still permitting the box to be rotated with the expenditure of but slight force. The invention proposes use of the box for all purposes which ordinary boxes are capable of use for, for instance by using partitions or division plates 9 of any number as depicted in Figure 3, the box may be used to contain 10 toilet sets or articles, ladies' sewing or embroidery sets, or confectionery, the box serving both to display the contents when on sale and to thereafter be used by the purchaser in preserving or storing such contents.

As illustrated in Figure 1, the box is provided with a dome-like filler 10 upon which various articles may be suitably supported for display by the merchant. For instance 20 watches and other articles of jewelry; druggists' supplies such as tooth brushes; pipes and cigar or cigarette holders; cutlery, and all other articles capable of being contained within the box may be arranged and displayed on the filler.

The invention also proposes use as a bead threader in which use the marginal wall or rim 11 of the box is vertically slotted at 12 and at regular intervals to admit a needle, 30 a preferably wooden block 13, secured by shellac being arranged within the box and provided with a series of spaced curved wells 14 which open through the block periphery, the wells having enlarged curved upper ends 15 which are of downwardly converging formation so as to direct the beads downwardly. The center of the block has a large circular compartment 16 for storing beads. As shown in Figure 7 the top has a pouring 40 hole 17, which can be turned to register with the various wells to enable the beads thereof to be emptied therefrom without disturbing the beads in the other wells. In use, the box is rotated to bring the beads in 45 the desired well in front of the user, whereupon the needle is thrust into the slot of that well to pick up or thread a bead thereon; the needle being finally moved upwardly until out of the slot, all as more particularly 50 described in my Patent No. 1,417,713 of May 30, 1922.

It is however to be expressly understood that the invention is susceptible of all of the various uses to which display boxes and 55 article containers and the like are capable of, and accordingly the recited instances of use are to be considered in the light of examples and not exhaustive enumeration of all possible uses to which the invention may 60 be put.

What is claimed is:

1. In a box, a body having a downwardly facing socket formed in its bottom, a cover for the box having a knob extending up-

wardly from its upper face and having a 65 circular series of teats surrounding the knob and rounded to form anti-friction bearings, the knob being formed to engage the fingers to allow of removal of the cover from the body and upon removal to extend 70 into the socket so as to rotatably support the body with the bottom thereof resting on said bearings, and a latch integral with the bottom of the body and having a socket 75 for receiving and frictionally engaging one of the bearings to hold the body against rotation.

2. In a box, a body having a downwardly facing socket formed in its bottom, a cover for the box having a knob extending upwardly from its upper face and having a 80 circular series of teats surrounding the knob and rounded to form anti-friction bearings, the knob being formed to extend into the socket so as to rotatably support the body with the bottom thereof resting on said bearings, and means on the body to 85 frictionally engage one of the bearings to hold the body against rotation.

3. In a box, a body having a socket in its bottom, a cover for the box having a knob extending upwardly from its upper face and receivable in the socket so as to rotatably support the body from the cover, and means 90 between the body and cover to hold the body against rotation relative to the cover.

4. In a box, a body having a socket in its bottom, a cover for the box having a knob extending upwardly from its upper face and receivable in the socket so as to 95 rotatably support the body from the cover, and frictional means between the body and cover to hold the body against rotation relative to the cover and to allow of rotation of the body upon exerting pressure on the latter.

5. In a box, a body, a cover therefor, and means between the body and cover to rotatably mount the body on the cover upon removal of the latter.

6. In a box, a body, a cover therefor, one of said parts having a knob and the other a socket to turnably receive the knob, whereby to enable the body to be rotatably supported by the cover upon removal of the latter.

7. In a box, a body, a cover therefor, means between the body and cover to rotatably support the body on and from the cover, and latching means between the body and cover to hold the parts against relative rotation.

8. In a bead threading device, a box having a body formed with spaced vertical needle-receiving slits in its rim, a member in the box having bead-receiving wells aligned with the respective slots, a cover for the box body, and means between the body

and cover for rotatably supporting the body separate compartments on its interior, a 10
from the cover. cover for the body, and interengaging means

5. In a box, a body having a series of between the body and cover whereby upon
bead compartments therein and having a removal of the cover the body may be
needle-receiving slot for each compartment, superposed thereon and rotatably support-
a cover for the body, and means to rotat-
ed thereby. 15
ably support the body from the cover upon
removal of the latter.

10. In a box, a body having a series of

In testimony whereof I affix my signature.

WILLIAM W. BOLLS.
